UNITED STATES PATENT OFFICE.

JOHN McMANUS, OF JET, OKLAHOMA.

TRAIN-STOP MECHANISM.

1,356,382.

Specification of Letters Patent. Patented Oct. 19, 1920.

Application filed January 29, 1920. Serial No. 354,949.

To all whom it may concern:

Be it known that I, JOHN McMANUS, a citizen of the United States, and a resident of Jet, in the county of Alfalfa and State of Oklahoma, have invented a new and Improved Train-Stop Mechanism, of which the following is a full, clear, and exact description.

This invention relates to improvements in train stop mechanisms, an object of the invention being to provide improved electrically controlled means for preventing train collisions and which is so constructed as to automatically stop both trains when two trains are on the same block.

A further object is to provide means for operating the brakes and closing the throttle of a locomotive and provide a fusible member controlling the operation of said means, said fusible member fused or burned by the explosion or burning of gasoline or similar material which is ignited by a spark caused by the closing of an electric circuit when two trains are on the same block.

With these and other objects in view the invention consists in certain novel features of construction, and combinations and arrangements of parts, as will be more fully hereinafter described and pointed out in the claims.

In the accompanying drawings—

Figure 1 is a view partly in elevation and partly in section illustrating my improvements;

Fig. 2 is an enlarged view in section on the line 2—2 of Fig. 1;

Fig. 3 is a diagrammatic plan view illustrating two locomotives on the same block which causes the operation of my improved train stop mechanism;

Fig. 4 is an enlarged view in section through the cup 31;

Fig. 5 is an enlarged view in section on the line 5—5 of Fig. 1; and

Fig. 6 is a fragmentary view in cross-section on an enlarged scale illustrating my improved electric connection with the locomotive wheel.

1 and 2 represent the rails of a single block and it is to be understood that the rails of one block will be insulated from the rails of adjacent blocks, as clearly shown in Fig. 3. A and B represent two locomotives which are illustrated on the same block in Fig. 3, and when two locomotives are on

the same block, my improved train stopping mechanism is caused to operate, as will more fully hereinafter appear. As all of the locomotives of the system will be equipped alike, the description hereinafter of one mechanism will apply alike to all.

The locomotive is provided with the ordinary throttle lever 3 and with an air cock 4 which controls the air brakes, and this cock and its coöperating parts may form an addition to the ordinary equipment of the locomotive, or may be connected to the equipment in ordinary use.

5 represents a weight which is connected by a chain 6 with the throttle lever 3 and is movable over a pulley 7 and through a guide 8. A branch chain 9 connects chain 6 with the arm 10 of the cock 4 and is guided in its movement by a pulley 11. Hence, when the weight 5 is permitted to fall, it will perform the double function of closing the throttle valve and opening the air cock 4 to apply the brakes. The guide 8, above referred to, is located at the free end of a curved arm 12 and the latter is fixed to a bracket 13.

A tilting support 14 is made with flanged edges 15 forming guides for flanges 16 at the sides of the weight 5. This support 14 is made with perforated lugs 17 on its under face and at one end mounted to turn on a rod 18 secured in fixed supports 19 so that the support 14 can swing on its pivot to release the weight 5, as will more fully hereinafter appear.

The weight 5 is appreciably longer than the support 14 and at its free end is provided with a roller 20 which normally rests upon a bifurcated tongue 21 constituting an integral part of a catch 22. The catch 22 operates to hold the weight in horizontal position, and when in this position, the free end of the support 14 rests upon the bracket 13. The catch 22 is in the form of a sliding block guided in its movement by a frame 23 having a bar 24 at one end which limits the movement of the catch in one direction. A chain 25 is connected to one end of the catch 22 and is passed over a pulley 26 and provided with a weight 27 at its free end tending to draw the catch away from the weight. A curved guide 28 is provided on the frame 23 and operates to guide the downwardly swinging movement of the roller 20 as the weight tilts from a hori-

zontal to a vertical position. The inner end of the catch 22 has a chain 29 secured thereto and passes around a pulley 30 on the frame 23. This chain 29 operates to hold the catch in normal position and must be released to allow the weight 27 to pull the catch out of engagement with the weight to allow the latter to fall. The control of this chain 29 constitutes one of the features of my invention and will now be described in detail.

A container 31, which may be in the form of a cup having a closed top 32, is secured to a fixed part of the locomotive and is provided with a crossbar 33 to which a fusible cord or other connecting device 34 is secured. This fusible device 34 extends through an opening 35 in the cover 32 and is secured to the chain 29. The container 31 is adapted to contain gasoline or other combustible material 36 and a spark plug 37 is supported in the container, and when a spark is generated, will cause the explosion of the gasoline and the burning of the fusible cord 34 to release the chain 29 and permit the operation of the weight, as above explained.

The spark of the plug 37 is generated electrically and I have illustrated diagrammatically the electric means employed. First, I include the forward pony wheel 38 at one side of the locomotive and the rear pony wheel 39 at the other side of the locomotive in a primary circuit including a battery 40, the primary winding of the spark coil S and its interrupter together with a manually operable switch 41, all carried by the locomotive. To further insulate the wheels of the locomotive I may provide insulating means 42, as shown in Fig. 1. The electric contacts for the wheels are illustrated best in Fig. 6. An arm 43 is carried by the axle box 44 and is provided at its outer end with a block of insulation 45 which supports a pin 46 having a head 47 at its inner end. This pin 46 is located in line with the center of the wheel 38 and receives a coiled wire 48, one end of which is fixed to the center of the wheel and is bowed, as shown at 49, to allow it to swing freely around the head. A ring 50 is located on the pin 46 and is held against the block 45 by the coiled wire 48, the latter constituting a coiled spring and an electric contact as well, so that the ring 50 and the wire 48 are maintained in electric contact at all times. The forward pony wheel at one side of the locomotive is electrically connected by a wire 51 with the battery 40 and a wire 52 connects the other side of the battery with the primary winding of the spark coil S. A wire 53 connects the interrupter of the spark coil S to the contact of the switch 41, and the arm 65 of the latter is connected to the wheel 39

at the other side of the locomotive as clearly shown in Figs. 1 and 3. The spark plug 37 is included in a secondary circuit which comprises the secondary winding of the spark coil S and the container 31, all connected by wires 37^a and 37^b in the manner shown in Fig. 3.

It will be noted, particularly by reference to Fig. 3, that the wheels at opposite sides of the locomotive pilot are insulated from each other, and this is illustrated more or less diagrammatically by the insulation shown at 42.

Fig. 6 shows in detail the electric contact between the wheels and the wires of the circuit. The coil 48, which is connected at one end, as shown at 49, to the center of the wheel, 38, revolves with the wheel around the pin 46 and is maintained in engagement with the contact ring 50. The pin 46 is carried by the block of insulation 45 and is in alignment with the center of the wheel 38.

Normally the parts are in the position shown in Fig. 1 with the bifurcated tongue 21 of the catch 22 located in a roller 20 and supporting the weight 5 in horizontal position with the chain 6 slack, the tongue 21 being bifurcated to accommodate the chain 29. The primary circuit remains open until two locomotives are on the same block 95 when the circuit is closed as follows: from the battery 40 of locomotive B, through the wire 51, to the wheel 38, through rail 2 to the wheel 38 of locomotive A, thence through wire 51 of locomotive A, to battery 40, wire 52, primary winding of spark coil S, wire 53, switch 41, and wire 54 to wheel 39 of locomotive A, thence through rail 1, to wheel 39 of locomotive B, and from the wheel 39 through the wire 54 of locomotive B to the switch 41, and from the latter through the wire 53, the primary winding of the other spark plug, and wire 52, to the battery 40 first referred to.

With the completion of the primary circuit, energization of the primary winding of the spark coils is effected which in turn energizes the secondary windings to generate the secondary circuits current of a sufficient potential to generate the proper spark at the terminals of the sparks 37. These sparks thus generated ignite the gasoline 36 in the containers and burn the fusible connections 34. When this happens, the weights 5 of the two locomotives exert a longitudinal pull on the catches 22 to move the tongues 21 from under the rollers 20. The weights 5 then tilt downwardly and slide out of the supports 14 exerting a pull on the chain 6 to operate the throttle lever 3 and the air cock 4 as will be readily understood.

The operation therefore is entirely automatic, stopping both locomotives, and this operation takes place only when two loco- 130

motives are on the same block, for otherwise the electric circuits are open and the parts remain in normal position.

Various slight changes may be made in 5 the general form and arrangement of parts described without departing from the invention, and hence I do not limit myself to the precise details set forth, but consider myself at liberty to make such changes and 10 alterations as fairly fall within the spirit and scope of the appended claims.

I claim:

1. The combination with a locomotive, and means for operating the brakes thereof, 15 of a container having combustible material therein, a fusible member in the container controlling the brake operating means, and a spark plug in the container included in an electric circuit with a source of electricity and certain of the wheels of the locomotive.

2. The combination with a locomotive, and means for operating the brakes thereof, 25 of a container having combustible material therein, a fusible member in the container controlling the brake operating means, a spark plug in the container included in an electric circuit with a source of electricity and certain of the wheels of the locomotive, 30 and the wheels at opposite sides of the locomotive insulated from each other.

3. The combination with a locomotive, and a weight adapted to operate the brakes, of means holding the weight against downward movement, a container having combustible material therein, a fusible member in the container controlling the fall of the weight, and a spark plug in the container included in an electric circuit with a source 35 of electricity and certain of the wheels of the locomotive.

4. The combination with a locomotive, of a tilting support in the locomotive, a weight on the tilting support constructed to operate the brakes of the locomotive, a container having combustible material therein, a fusible member in the container controlling the tilting of the support, and a spark plug in the container included in an electric circuit with a source of electricity and certain 45 of the wheels of the locomotive.

5. The combination with a locomotive, of a tilting support in the locomotive, a weight on the tilting support constructed to operate the brakes of the locomotive, a sliding catch holding the weight in horizontal position on the tilting support, a container having combustible material therein, a fusible member in the container controlling the 55 operation of the catch, and a spark plug in the container included in an electric circuit with a source of electricity and certain of the wheels of the locomotive.

6. The combination with a locomotive, of 60 a tilting support in the locomotive, a weight

on the tilting support constructed to operate the brakes of the locomotive, a sliding catch holding the weight in horizontal position on the tilting support, a container having combustible material therein, a fusible member in the container controlling the operation of the catch, a weight adapted to move the catch, a flexible device connected to the catch and to the fusible member holding the catch in normal position, and a spark 70 plug in the container included in an electric circuit with a source of electricity and certain of the wheels of the locomotive.

7. The combination with a locomotive, of a tilting support in the locomotive, a weight having flanged guiding connection with the support, said weight adapted to operate the air brakes of the locomotive, a sliding catch supporting the free end of the weight and holding the latter in normal 80 horizontal position, a roller on the free end of the weight, a curved guide against which the roller swings as the weight moves downwardly, a container having combustible material therein, a fusible member in the container controlling the operation of the catch, and a spark plug in the container included in an electric circuit with a source of electricity and certain of the wheels of the locomotive. 85

8. The combination with a locomotive having a throttle valve and an air brake thereon, of a weight, a chain connected to the weight and to the throttle valve, a branch chain connecting the first-mentioned chain with the air brake valve, means supporting the weight, a container having combustible material therein, a fusible member in the container controlling the release of the weight, and a spark plug in the container included in an electric circuit with a source of electricity and certain of the wheels of the locomotive. 95

9. The combination with a locomotive, of a container in the locomotive having combustible material therein, a fusible link in the container, means operatively connected to the fusible link and adapted when the link is broken to operate the air brake and the throttle valve of the locomotive, and a spark plug in the container included in electric circuit with a source of electricity and certain of the wheels of the locomotive. 100

10. The combination with a locomotive, and means for operating the brakes thereof, of a flexible device controlling the release of said brake operating means, a container having combustible material therein, a cross-bar in the container, a fusible member connecting the flexible member with said cross-bar, and a spark plug in the container included in an electric circuit with a source of electricity and certain of the wheels of the locomotive. 115

11. The combination with a locomotive, of 120

brake operating means on the locomotive, electric contacts on the forward pony wheel of the locomotive at one side and on the rear pony wheel at the other side, said contacts comprising a support, a pin projecting from the support toward the center of the wheel, a collar on the pin and insulated from the support, a spring wire coiled around the pin

bearing against the collar, an extension on one end of the coil secured in the center of the wheel, and electrically controlled means for operating the brake controlling means and included in an electric circuit with said contacts.

JOHN McMANUS.
